UNITED STATES PATENT OFFICE.

GEORGE E. WEBB, OF MILWAUKEE, WISCONSIN, ASSIGNOR TO KOEHRING COMPANY, OF MILWAUKEE, WISCONSIN, A CORPORATION.

AUTOMATIC DISCHARGE FOR CONCRETE MIXERS.

Application filed January 30, 1925. Serial No. 5,827.

Concrete mixing machines are customarily equipped with discharge means, usually in the form of a discharge chute, by which the contents of the mixing drum of the machine 5 are adapted to be discharged after the lapse of a proper mixing period, or such machines are adapted to be controlled by the tilting of their drums for the purpose of shifting the drum into such a position that the contents thereof will be discharged by gravity.

The primary object of this invention has been to provide a novel mechanical means for enabling power to be utilized in the discharge operation of a mixing machine, said 15 operation being today largely effected by manual means. In the operation of the large mixers which are quite commonly manufactured at the present time, the operation of the discharge mechanism by manual means 20 is quite arduous, and it is the aim of the present improvements to relieve the operator of all labor in connection with the discharging of the mixer, and if desired, to relieve him of any controlling function respecting 25 said operation. Additionally it is designed to save time in the operation of the discharge of the machine by the efficient automatic power control means involved in the present improvement.

30 In carrying out the invention the general plan of the automatic operation of certain parts of the mixer is in accordance with the general principles of construction fully set forth in Patent No. 1,370,497 which was granted on March 1, 1921 to Robb, utilized 35 in connection with an automatic time control mechanism such as that disclosed by Patent No. 1,451,483 which was granted on April 10, 1923 to Winkler, or the Patent No. 40 1,321,460 which was granted on November 11, 1919 to Lichtenberg.

In the carrying out of the present invention other special objectives are the designing of positive driving mechanism for the 45 discharge chute of the mixer, well suited to commercial conditions of space, and operating efficiency, which mechanism does away entirely with the necessity of employing clutches such as are required to be manually 50 operated in order to initiate the operation of the discharge means in bringing the same either to discharging or non-discharging positions. By the elimination of clutches I do away with the disadvantages of the complicated 55 constructions of such parts and the

wear and tear incident to the operation of such parts, and at the same time the heretofore manual operation of such clutches is dispensed with through the automatic provisions that I have developed in conjunction 60 with my discharge chute operating means.

The invention additionally includes special provisions whereby the operator of the machine is enabled to take manual control of the discharge chute if desired; provisions 65 by which the operator may block or retard the discharge from the mixer should he desire to hold the contents in the drum after the expiration of the usual mixing period; and other provisions preventing the operator from causing the discharge of the contents of the drum prior to the lapse of the proper mixing period as determined by the timing mechanism or batch meter.

70 While one particular embodiment of the invention will be shown and described in detail for illustrative purposes, it will be understood that I do not restrict myself to the exact construction shown and that many modifications and changes can be made in 75 the details of construction without departing from the spirit of the invention.

For a full understanding of the invention reference is to be had to the following description and accompanying drawings in 80 which—

Figure 1 is a side elevation of a fragmentary portion of a concrete mixing machine having the invention applied thereto.

Figure 2 is an end view of the same.

Figure 3 is a detail view of the power control mechanism, showing the parts thereof in normal position.

Figure 4 is a similar view with the parts shown in the position assumed after the gear turning lever has been released.

Figure 5 is a detail view illustrating the action of the trip mechanism during the release of the detent which controls the gear moving lever.

Figure 6 is a plan view of the detent and associated trip mechanism.

Figure 7 is a longitudinal sectional view through the safety coupling or clutch connection between the discharge chute operating shaft and the power mechanism, the clutch parts being shown in operative engagement with each other.

Figure 8 is a similar view taken on a plane at substantially right angles to that of Fig.

ure 7, the clutch parts being shown in the position assumed when disengaged from each other.

Figure 9 is an end view of the safety coupling.

Fig. 10 is a transverse section taken on the plane indicated by line 10—10 of Fig. 8 and looking in the direction indicated by the arrows.

Corresponding and like parts are referred to in the following description and indicated on all of the views of the drawings by like reference characters.

For the purpose of illustration the discharge control mechanism of this invention is shown as mounted upon a conventional and well known type of concrete mixer which includes a mixing drum A and associated discharge chute B, having the general construction and mounting which is clearly disclosed in Patent No. 1,126,487 which was granted to Koehring on January 26, 1915. The mixing drum A is provided with the external gears C which engage suitable driving pinions, not shown, whereby rotation of the drum is effected from any suitable source of power. The discharge chute B is connected by the usual linkage D to an arm E on the chute operating shaft 1. By rotating this shaft in reverse directions the discharge chute can be swung through an angle of approximately 90° and caused to assume either the non-discharging position, indicated by dotted lines in Figure 1, or the discharging position, indicated by full lines in Figure 1. A conventional loading skip F is employed for supplying the unmixed aggregates to the drum A and suitable means, not shown, may be utilized for supplying the necessary moisture or water to the aggregates which are fed into the mixing drum from the loading skip. When the loading skip is swung upwardly into the position indicated by Figure 1 on the drawings, the unmixed aggregates which have previously been deposited in the same will slide downwardly and be discharged by gravity into the mixing drum.

A suitable timing mechanism or batch meter G is utilized for measuring the mixing period for the successive batches of materials which are fed into the drum. In order to produce proper concrete it is of importance that all of the batches should be thoroughly and properly mixed and also that the mixing time for each batch should be substantially the same so that a uniform output is obtained. Various forms of mechanisms have heretofore been devised for measuring or timing the mixing period so that all of the batches passing through the mixer will be uniformly and properly mixed, and the timing mechanism G which is shown on the drawing may be of a type which is fully disclosed in the Winkler Patent No. 1,451,483

which was granted on April 10, 1923. When the loading skip F is swung upwardly to deliver the contents thereof into the mixing drum it engages a plunger 2 and moves the same forwardly, thereby swinging a lever 3 on the timing mechanism G and setting the mechanism for operation. At the expiration of the proper mixing period, as determined by the mechanism of the batch meter G, an arm 4 at one side of the batch meter casing 7 is swung upwardly, said arm being connected by a link 5 to an arm 6 of the power control mechanism.

The power control mechanism is housed within a casing 7 which is suitably arranged under the batch meter or timing mechanism G. A power shaft 8, which is substantially parallel with the axis of the mixing drum, extends into the casing 7 and is suitably journaled in the sides thereof. The portion of the power shaft 8 which is within this casing has a worm 9 keyed thereon, while the other end of the power shaft is provided with a pinion 10 which meshes with one of the external gears of the mixing drum. The bracket H which supports the timing mechanism G and casing 7 is provided with a bearing 11 which receives the power shaft 8 at a point adjacent to the pinion 10 and serves to support and position the shaft so that the pinion will be maintained in proper mesh with the gear C of the drum. The power shaft is thus driven continually from the drum as long as the mixer is in operation.

Journaled within the casing 7 and arranged above the power shaft 8 is a mutilated worm gear 12. This mutilated gear 12 is keyed upon a shaft 13 which is journaled in the casing 7 and extends through one of the side walls thereof, the outer end of the shaft being provided with an arm 14 which is connected by a downwardly extending link 5 to a corresponding arm or lever 6 on the chute operating shaft 1. The mutilated gear has two cut-away portions 17 which are arranged substantially 180° apart, and each of which is sufficiently large to receive the worm 9. It will be understood, however, that by moving the worm gear to bring the teeth thereof into mesh with the constantly rotating worm 9, the gear 2 will be forcibly rotated by the worm until the worm overrides the teeth thereof and again enters one of the cut-away portions or recesses 17. This rotation of the mutilated worm gear and shaft through an angle of 180° serves to rotate the chute operating shaft 1, as will be hereinafter described to swing the discharge chute into either a discharging or non-discharging position.

The mutilated gear wheel 12 is provided upon one side thereof with a hub portion 18 having opposed flat sides or seats 19 which are 180° apart. One arm of a bell crank neutralizing lever 20 is adapted to bear re-

silently against one of the flat sides 19 of the hub to hold the worm gear in neutral position with the rotating worm 9 received in one of the recessed portions 17 of the 5 mutilated gear wheel. The other arm of the bell crank lever is connected by a tension spring 21 to a starting lever 22 which is pivoted between its ends on the shaft 23. One end of the starting lever has a nose 10 22^a which is adapted to engage either one of a pair of pins 24 which project laterally from the mutilated gear wheel. The other end of the starting lever is adapted to be engaged by a detent 25 which normally holds 15 the starting lever in inoperative position, thereby retaining the spring 21 under tension and holding the arm of the bell crank lever against one of the flat sides or seats 19 of the gear wheel hub so that the gear 20 wheel is maintained in neutral position. The detent is rigid with a short shaft 26 which is journaled in one of the side walls of the casing 7 and extends through the casing. The projecting end of the said 25 shaft is shown as having a hand lever 27 applied thereto for use in manual control of the detent member under certain conditions of operation. A tail piece 25^a projects rearwardly from the pivot end of the detent 30 25 and is provided with a curved or segmental portion 25^b which is slotted longitudinally to receive the curved end of a locking pawl 28. The locking pawl is pivotally connected at 29 to the end of an arm 30 which is rigid with the inner end of a short 35 shaft 31, said shaft being journaled in a side wall of the casing 7 and extending through the same. The outer end of the shaft 31 has the arm 6 rigidly applied thereto, said 40 arm being connected with the batch meter or timing mechanism G through the medium of the link 5 and arm 4 as previously described.

Connecting the tail piece 25^a of the detent 25 to the locking pawl 28 is a tension spring 32 which normally tends to swing the locking pawl toward the inner end of the slot 33 and cause the nose 34 of the locking pawl to engage the tail piece 25^a to limit 45 the swinging movement of the detent in one direction. Swinging movement of the detent in the other direction is prevented by a shoulder 35 which projects laterally from the locking pawl, said shoulder engaging one side of the tail piece 25^a, while the nose 50 of the pawl normally engages the other side of the tail piece, the shoulder and nose then cooperating with each other to prevent a swinging movement of the detent in either direction without producing a corresponding 55 movement of the arm 30 and short shaft 31, which movement is prevented by reason of the fact that the arm 6 at the outer end of the said shaft 31 is connected by the link 60 5 to the arm 4 of the batch meter or timing

mechanism G. The free end of the locking pawl terminates in a curved or cam portion 36, which is adapted to engage a round hub portion 37 on one side of the mutilated gear wheel 12. The round hub portion 37 projects upon one side of the mutilated gear wheel 12, while the hub portion 18 with the flat seats 19 projects from the opposite side thereof. 70

At the expiration of the proper determined mixing period, as measured by the timing mechanism G, the arm 4 of the timing mechanism is rotated upwardly to pull upwardly on the link 5. This motion is transmitted through the arm 6, short shaft 31, and arm 30 to the locking pawl 28. The nose 34 of the locking pawl is then in engagement with the tail piece 25^b of the detent, with the result that this movement of the locking pawl swings the detent 25 and 80 releases the starting lever 22. Just after the starting lever is released the cam shaped end 36 of the locking pawl is brought into engagement with the hub 37 of the mutilated gear wheel, and rides thereon, whereby the locking pawl is swung about its pivot 29 to produce tension in the spring 32 and return the detent 25 to its original position, so that it will automatically engage the 85 starting lever to reset the mechanism when the starting lever is swung back to its original position. 90

As soon as the starting lever 22 is thus released by the trip mechanism it is swung about its pivotal mounting by the energy 100 stored in the spring 21 and the nose 22^a thereof brought into a forcible engagement with either one of the pins 24 on the mutilated gear wheel 12. The tension of the spring 21 is thus very materially decreased when the 105 starting lever is released and the bell crank lever 20 accordingly bears with less force on the flat side of the hub 18, thereby making it less difficult to overcome the action of the neutralizing bell crank lever 20 and 110 impart movement to the gear wheel. The action of the starting lever on the pin 24 is sufficient to produce an initial rotation of the gear wheel and bring the teeth thereof into mesh with one end of the worm 9. The 115 gear wheel will then be positively rotated by the worm, although at a considerable reduction in speed, until the worm over-rides the teeth of the gear wheel and enters the recessed portion 17 at the opposite side 120 thereof. The mutilated gear wheel 12 and shaft 13 will then have completed substantially a one-half rotation and, as will be subsequently described, this acts to shift the discharge chute from either a discharging 125 or non-discharging position into the opposite position. Before the mutilated gear completes the one-half revolution one of the pins 24 thereon engages a cam 38 on the starting lever 22 and swings the said start- 130

ing lever back to its original position, whereupon it is automatically engaged by the detent 25. The shoulder or projection 35 on the locking pawl 28 makes it impossible to manually release the detent 25 until after the termination of the proper mixing period as measured by the batch meter G, although by holding the hand lever the releasing of the detent and discharge of the batch can be delayed as long as desired after the expiration of the predetermined mixing period. It is thus impossible for the operator to discharge the batch until after it has remained in the mixing drum for the full predetermined period of time as measured by the batch meter, although the operator can keep the batch in the mixing drum for a longer period of time if he so desires. A distinct advantage arises from connecting the spring 21 of the starting lever to the neutralizing lever 20. When the mechanism is set the tension of this spring causes the neutralizing lever to press against a flat-side 19 of the hub 18 with a considerable amount of force so that there is no possibility of the mutilated worm gear being brought prematurely into engagement with the worm, although as soon as the starting lever is released the tension of the said spring is greatly reduced so that the resistance to the initial rotation of the mutilated gear is greatly decreased. It will also be noted that there are rounded corners 19^a at the ends of the flat seats 19 of the hub 18 which make it easier for the neutralizing lever to ride out of engagement with the flat seats.

Provision is made for preventing premature actuation of the chute operating means by pulling downwardly on the connecting rod 15 and imparting a sufficient rotary movement to the crank arm 14 and shaft 13 to bring the two gears into mesh. The starting lever 22 is provided with an arm 50, shown by Figs. 3, 4 and 5, which projects laterally therefrom and normally has the end thereof positioned just in front of the upper pin 24 of the mutilated gear wheel. As long as this arm is directly in the path of the said pin 24 it provides a positive stop for preventing any initial rotation of the gear wheel to bring the teeth thereof into mesh with the worm. However, as soon as the starting lever 22 is released by the detent 25 the stop arm 50 is swung upwardly out of the path of the upper pin 24 during the slight initial movement of the starting lever which is necessary to bring the nose 22^a at the lower end thereof into engagement with the lower pin 24, the position of the stop arm 50 when it is swung into inoperative position being indicated by Figure 5. The stop arm 50 does not interfere at all with the normal operation of the trip mechanism but cooperates with the uppermost pin 24 to provide a lock-

ing means which prevents the mutilated gear from being rotated independently of the trip means, as by pulling downwardly on the rod 15 and thereby swinging the crank arm 14 and turning the shaft 13. The operator of the mixing device is thus prevented from cheating the timing mechanism and causing the contents of the mixing drum to be discharged before the trip mechanism is actuated by the timing device.

When the mutilated gear 12 is actuated the arm 14 at the outer end of the gear shaft 13 is correspondingly moved and motion is transmitted from this arm through the link 15 to the arm 16 which is loose on the chute operating shaft 1. This arm is interposed between a collar 39 which is fixed on the shaft and a clutch member 40 which is keyed upon the shaft at 41, so that it rotates with the shaft but is free to slide longitudinally thereon. The clutch member has a hollow cylindrical formation, and a spring 42 is housed therein, one end of the spring bearing against the clutch member while the other end thereof bears against a plate 43 which is rigidly applied to the shaft and closes the open end of the spring receiving chamber provided in the interior of the clutch member. The clutch member telescopes over the plate 43 when it is moved against the action of the spring, and a valved grease inlet 44 on the plate 43 enables the spring receiving chamber to be filled with grease or oil after the parts have been assembled. The end of the clutch member 40 which is adjacent to the arm 16 is provided upon diametrically opposite sides thereof with recesses 45 having inclined side walls. The adjacent side of the hub portion of the link 15 is provided with corresponding lugs 46 which have inclined sides and are adapted to enter the recesses 45 to produce a clutch connection between the arm 16 and the chute operating shaft 1. The shaft 1 ordinarily rotates with the arm 16, although in the event there is any unusual resistance to the rotation of the shaft, the inclined or cam sides of the clutch lugs 46 and recesses 45 will cooperate with each other to slide the clutch member 40 against the action of the spring 42 and break the clutch connection between the arm 16 and the shaft, thereby preventing breakage or dangerous straining of the parts.

As previously explained, the chute operating shaft 1 is connected in any suitable manner as by means of the conventional linkage D to the discharge chute B, so that by alternately oscillating the shaft in opposite directions the discharge chute can be swung from either a discharging or non-discharging position into the opposite position. However, should the shaft 1 be prevented from rotating for any reason, as by the lodgement of a stone or other obstruc-

tion between the link members where they project into the drum or by excess accumulation of concrete on the sub-chute, the safety coupling provided by the clutch device 5 will cause the driving connection between the power shaft 8 and chute operating shaft 1 to be broken so that breakage of the parts will be prevented.

It will be noted that the mutilated gear 10 gear 12 and its shaft 13 always revolve in the same direction, while the chute operating shaft 1 oscillates in opposite directions. This is made possible by the fact that the arm 14 of the mutilated gear shaft 13 is 15 shorter than the arm 16 on the chute operating shaft 1. The arm 14 turns through an angle of approximately 180° each time it is operated, while the arm 16 moves back and forth through an angle which is less 20 than 180°, the exact movement being just that which is required for operating the discharge chute through the linkage D.

In mixing a batch of concrete it will be apparent that when the unmixed aggregates 25 are deposited in the drum A from the loading skip F, the mechanism of the batch meter G is started into operation. It is impossible for the operator to manipulate the hand lever 27 to release the trip mechanism 30 of the power device and bring about a discharge of the batch until before the completion of the mixing period as determined by the batch meter. At the expiration of this predetermined time the batch meter pulls 35 upwardly on the link 5 and thereby releases the detent 25 of the power device, as previously described. The mutilated gear wheel is then brought into action by the starting lever 22, whereby power is transmitted from 40 the power shaft 8 to the chute operating shaft 1 to rotate the said shaft a sufficient amount to swing the discharge chute B into discharging position, whereupon the properly mixed batch of concrete is discharged 45 from the drum. As soon as the batch has been discharged the operator can manipulate the hand lever 27 to move the detent 25 and release the starting lever 22, whereupon there is another cycle of operation of the 50 power mechanism to return the discharge chute to non-discharging position. As soon as the next successive batch is deposited in the mixing drum the timing mechanism or batch meter G is reset as previously described, whereupon the link 5 is moved 55 downwardly and the locking pawl 28 brought into positive position to render it impossible for the detent 25 to be again released by the hand lever until after the proper mixing period has completely expired. It will be obvious that, if desired, the second cycle of operation of the power mechanism required to return the discharge chute to non-discharging position could be 60 readily provided for automatically by a

linkage connection arranged for actuation by the skip.

While the power discharge mechanism has been shown as applied to a mixer of that type which is provided with a tilting 70 discharge chute, it will be understood that the power mechanism can be utilized for operating the discharge mechanism of any type of mixer, including those mixers which are so mounted that the drums can be rotated to admit of the batch falling from the drum by gravity.

The arm 30 and arm 6 constitute in effect what may be termed a detent releasing lever, said lever being releasably connected 80 to the detent 25 by means of the locking pawl 28. When this detent releasing lever is actuated by the timing mechanism G the detent is disengaged from the starting lever 22, whereupon the gear members are 85 brought into initial engagement and the mutilated gear driven by power through a half revolution to swing the discharge chute from a non-discharging position into a discharging position or vice versa. The casing 90 within which the power mechanism is located may be supplied or filled with a lubricant so that the gear members and associated parts will operate in oil, thereby preventing undue wear upon the mechanism and enable 95 it to stand up successfully under long periods of hard usage.

Having thus described my invention what I claim as new and desire to secure by Letters Patent is—

1. In combination, a power driven mixer, charging means for the mixer, discharging means for the mixer, power means driven by the mixer for actuating the discharge means, and timing mechanism controlled by the charging means and controlling the said power means.

2. In combination, a power driven mixer, charging means for the mixer, discharging means for the mixer, power means driven from the mixer for intermittently actuating the discharging means, and timing mechanism controlled by the charging means and controlling the intermittent action of the said power means.

3. In combination, a mixer, discharging means for the mixer, a constantly driven power member, timing mechanism, and means controlled by the timing mechanism for intermittently connecting the said power member to the discharging means.

4. In combination, a mixer, discharging means for the mixer, a constantly driven power member for intermittently actuating the discharging means, timing mechanism automatically controlling the actuation of the discharging means, and manual means for controlling the actuation of the discharging means.

5. In combination, a mixer, discharging

means for the mixer, a constantly driven power member for intermittently actuating the discharge means, timing mechanism automatically controlling the said intermittent action, manual means for controlling the intermittent action of the discharging means, and means for rendering the said manual means inoperative until after the completion of the operation of the timing mechanism.

6. In combination, a mixer, discharging means for the mixer, a constantly driven power member, a second power member driven intermittently thereby and operatively connected to the discharge means, timing mechanism for the mixer, and means operated by the said timing mechanism for causing the intermittently driven power member to be actuated by the constantly driven power member.

7. In combination, a mixer, discharging means for the mixer, a constantly driven power member, a second power member driven intermittently thereby and operatively connected to the discharging means for actuating the latter, timing mechanism for the mixer, means controlled by the timing mechanism for causing an actuation of the intermittently driven power member, and manual means for causing an actuation of the intermittently driven power member, said manual means being inoperative until after the full operation of the timing mechanism has been completed.

8. In combination, a mixer, discharging means for the mixer, a constantly driven power member, a second power member driven intermittently thereby and operatively connected to the discharge means, trip means controlling the intermittent operation of the second power member, timing mechanism for the mixer, and an operative connection between the timing mechanism and the trip means.

9. In combination, a mixer, discharging means for the mixer, a constantly driven power member, a second power member driven intermittently thereby, trip means controlling the intermittent action of the second power member, timing mechanism for the mixer, an operative connection between the timing mechanism and the trip means, manual means for releasing the trip means, and means for preventing manual release of the trip means until after the timing mechanism has completed its full operation.

10. In combination, a mixer, discharging means for the mixer, a constantly driven gear, an intermittently driven gear having a mutilated portion normally receiving the constantly driven gear and operatively connected to the discharge means, and means for initially moving the intermittently driven gear into mesh with the constantly

driven gear whereby the former is driven to actuate the discharge means.

11. In combination, a mixer, discharge means for the mixer, a constantly driven gear, an intermittently driven gear having a mutilated portion receiving the constantly driven gear, means for initially moving the intermittently actuated gear to bring it into mesh with the constantly driven gear, neutralizing means for stopping the intermittently driven gear when the constantly driven gear over-rides the same and enters the mutilated portion thereof, and an operative connection between the intermittently driven gear and the discharge means.

12. In combination, a mixer, discharge means for the mixer, a constantly driven gear, an intermittently driven gear operatively connected to the discharge means and having a mutilated portion normally receiving the constantly driven gear, yielding means tending to lock the intermittently driven gear at rest with the constantly driven gear in inoperative position within the mutilated portion thereof, starting means for initially moving the intermittently driven gear to overcome the locking means and bring the gear into mesh with the constantly driven gear, and means for decreasing the effectiveness of the locking means when the starting means is brought into action.

13. In combination, a mixer, discharging means for the mixer, a constantly driven gear, an intermittently driven gear operatively connected to the discharge means and having a mutilated portion normally receiving the constantly driven gear, a starting member adapted to engage the intermittently driven gear to bring the same initially into mesh with the constantly driven gear, a flat seat carried by the intermittently driven gear, a neutralizing lever adapted to engage the flat seat to stop the movement of the gear when the constantly driven gear enters the mutilated portion thereof, and a tension spring connecting the neutralizing lever and starting member, the stored energy of the spring serving to operate the starting member and the tension of the spring being thereby reduced so that there is less resistance by the neutralizing lever to the action of the starting lever.

14. In combination, a mixer, discharge means for the mixer, a constantly driven gear, an intermittently driven gear operatively connected to the discharge means and having a mutilated portion normally receiving the constantly driven gear, a starting lever adapted to engage the intermittently driven gear for bringing the same initially into mesh with the constantly driven gear, a detent normally holding the starting lever in inoperative position, a neutralizing lever tending to prevent rotation of the inter-

mittently driven gear when the constantly driven gear is inoperative within the mutilated portion of the intermittently driven gear, a spring connecting the neutralizing lever and starting lever and providing the power for actuating the starting lever when released, the utilization of the stored energy of the spring for actuating the starting lever serving to reduce the action of the spring 5 on the neutralizing lever so that resistance of the neutralizing lever to start the gear is reduced, and means for automatically resetting the starting lever before the constantly driven gear again enters the mutilated portion of the intermittently driven gear.

15. In combination, a mixer, discharge means for the mixer, a constantly driven gear, an intermittently driven gear operatively connected to the discharge means and having a mutilated portion normally receiving the constantly driven gear, a starting lever for moving the intermittently driven gear to bring it into initial engagement with the constantly driven gear, a detent normally holding the starting lever in inoperative position, timing means for the mixer, and means actuated by the timing means for automatically releasing the detent.

20 16. In combination, a mixer, discharging means for the mixer, a constantly driven gear, an intermittently driven gear operatively connected to the discharge means and having a mutilated portion normally receiving the constantly driven gear, a starting lever for moving the intermittent gear to bring it into engagement with the constantly driven gear, a detent normally holding the starting lever in inoperative position, timing mechanism for the mixer, a detent operating lever connected to the said timing mechanism, and a releasable connection between the detent operating lever and the detent.

25 17. In combination, a mixer, discharge means for the mixer, a constantly driven gear, an intermittently driven gear operatively connected to the discharge means and provided with a mutilated portion normally receiving the constantly driven gear, a starting lever adapted to move the intermittently driven gear to bring it into initial engagement with the constantly driven gear, a detent normally holding the starting lever in inoperative position, timing mechanism 30 for the mixer, a detent operating lever connected to the timing mechanism, a releasable connection between the detent operating lever and the detent, means for automatically releasing the said connection and returning the detent to its original position after the actuation thereof, and means for resetting the gear actuating lever.

35 18. In combination, a mixer, discharge means for the mixer, a constantly driven

gear, an intermittently driven gear operatively connected to the discharge means and having a mutilated portion normally receiving the constantly driven gear, a starting lever for moving the intermittently driven gear to bring it into initial mesh with the constantly driven gear, a detent normally holding the starting lever in inoperative position, timing mechanism for the mixer, a detent operating lever operatively connected to the said timing mechanism, a locking pawl releasably connecting the detent operating lever and detent, means for automatically releasing the pawl and returning the detent to its original position 40 after the detent has been actuated, and means actuated by the gearing for resetting the starting lever.

19. In combination, a mixer, discharge means for the mixer, a constantly driven gear, an intermittently driven gear operatively connected to the discharge means and having a mutilated portion normally receiving the constantly driven gear, a starting lever for moving one of the gears into initial mesh with the other gear, a detent normally holding the starting lever in inoperative position, timing mechanism for the mixer, a detent operating lever operatively connected to the said timing mechanism, a locking pawl operatively connecting the detent operating lever to the detent, cam means for automatically releasing the pawl after the detent has been actuated, and means actuated by the gearing for resetting the starting lever.

20. In combination, a mixer, discharge means for the mixer, a constantly driven gear, an intermittently driven gear operatively connected to the discharge means and having a mutilated portion normally receiving the constantly driven gear, a starting lever for moving one of the gears into initial engagement with the other gear, a detent for holding the starting lever in inoperative position, timing mechanism for the mixer, a detent operating lever operatively connected to the timing mechanism, a locking pawl connecting the detent operating lever and the detent, said locking pawl having a cam portion which engages a part of one of the gear members for automatically releasing the pawl after the detent has been actuated, and means for resetting the starting lever.

21. In combination, a mixer, discharge means for the mixer, a constantly driven gear, an intermittently driven gear operatively connected to the discharge means and having a mutilated portion normally receiving the constantly driven gear, a starting lever for moving one of the gears to bring it into initial engagement with the other gear, a detent normally holding the starting lever in inoperative position, timing mecha-

- 5 nism for the mixer, a detent operating lever operatively connected to the timing mechanism, a locking pawl connecting the detent operating lever and the detent, means for automatically releasing the locking pawl when the detent is released, resilient means controlled by the locking pawl for restoring the detent to its original position, and means for resetting the starting lever.
- 10 22. In combination, a mixer, discharge means for the mixer, a constantly driven gear, an intermittently driven gear operatively connected to the discharge means and having a mutilated portion normally receiving the constantly driven gear, a starting lever for moving one of the gears into initial engagement with the other gear, a detent normally holding the starting lever in inoperative position, timing mechanism for the 15 mixer, a detent operating lever operatively connected to the timing mechanism, a releasable connection between the detent and detent operating lever, yielding means controlled by the said releasable mechanism for returning the detent to its original position after it has been actuated, and means for resetting the starting lever.
- 20 23. In combination, a mixer, discharge means for the mixer, a constantly driven gear, an intermittently driven gear operatively connected to the discharge means and having a mutilated portion normally receiving the constantly driven gear, a starting lever adapted to move one of the gears into initial engagement with the other gear, a detent normally holding the starting lever in inoperative position, timing mechanism for the mixer, a detent operating lever operatively connected to the timing mechanism, a locking dog releasably connecting the detent operating lever and detent, said locking pawl having a cam nose, and one of the gear members having a hub portion which is engaged by the cam nose and operates therewith to automatically disengage the locking pawl and release the detent after the detent has been actuated.
- 25 24. In combination, a mixer, discharge means for the mixer, a constantly driven gear, an intermittently driven gear operatively connected to the discharge means and having a mutilated portion normally receiving the constantly driven gear, a pin projecting laterally from the intermittently driven gear, a starting lever having a portion adapted to engage the pin to move the intermittently driven gear to bring it into initial mesh with the constantly driven gear, a detent normally holding the starting lever in inoperative position, trip means controlling the detent, and a cam portion on the lever projecting into the path of the before mentioned pin for resetting the lever.
- 30 25. In combination, a mixer, discharge means for the mixer, a constantly driven gear, an intermittently driven gear operatively connected to the discharge means and having a mutilated portion normally receiving the constantly driven gear, a starting lever in inoperative position, timing mechanism for the mixer, a detent normally holding the starting lever in inoperative position, timing mechanism for the mixer, a detent operating lever operatively connected with the timing mechanism, a locking pawl carried by the detent operating lever and formed with a shoulder preventing relative movement of the detent in one direction, and a nose preventing relative movement of the detent in the other direction, means for automatically releasing the nose and causing the detent to return to its original position after it has been actuated, and means for restoring the starting lever.
- 35 26. In combination, a mixer, discharge means for the mixer, a constantly driven gear, an intermittently driven gear operatively connected to the discharge means and having a mutilated portion normally receiving the constantly driven gear, a starting lever for moving one of the gears to bring it into initial engagement with the other gear, a detent normally holding the starting lever in inoperative position, timing mechanism for the mixer, a detent operating lever operatively connected to the timing mechanism, a locking dog releasably connecting the detent operating lever and detent, said locking pawl having a cam nose, and one of the gear members having a hub portion which is engaged by the cam nose and operates therewith to automatically disengage the locking pawl and release the detent after the detent has been actuated.
- 40 27. In combination, a mixer, discharge means for the mixer, a constantly driven gear, a gear adapted to be driven intermittently by the constantly driven gear and operatively connected to the discharge means, and starting means for initially bringing the two gears into mesh to actuate the discharge means.
- 45 28. In combination, a mixer, discharge means for the mixer, a constantly driven gear, a second gear member operatively connected to the discharge means and adapted to be brought intermittently into engagement with the constantly driven gear, starting means for bringing the two gear members initially into mesh with each other to produce an actuation of the discharge means, and timing mechanism operatively connected to the starting means.
- 50 29. In combination, a mixer, discharge means for the mixer, a constantly driven gear, an intermittently driven gear having a mutilated portion normally receiving the constantly driven gear and operatively connected to the discharge means, and starting means for initially moving one of the gears to bring it into mesh with the other gear to

produce an actuation of the discharge means.

30. In combination, a mixer, discharge means for the mixer, a constantly driven gear, a second gear operatively connected to the discharge means and adapted to be intermittently driven by the constantly driven gear, a starting lever for moving one of the gears to bring it into initial engagement with the other gear to produce an actuation of the discharge means, a detent normally holding the starting lever in inoperative position, timing means for the mixer, and means actuated by the timing means for automatically releasing the detent.

31. In combination, a mixer, discharge means for the mixer, a constantly driven gear, a second gear operatively connected to the discharge means and adapted to be driven intermittently by the constantly driven gear, a starting lever for moving one of the gears to bring it into initial mesh with the other gear and produce an actuation of the discharge means, a detent normally holding the starting lever in inoperative position, timing mechanism for the mixer, a detent operating lever operatively connected to the said timing mechanism, and a releasable connection between the detent and detent operating lever.

32. In combination, a mixer, discharge means for the mixer, a constantly driven gear, a second gear operatively connected to the discharge means and adapted to be intermittently driven by the constantly driven gear, a starting lever for moving one of the gears to bring it into initial mesh with the other gear to produce an actuation of the discharge means, a detent normally holding the starting lever in inoperative position, timing mechanism for the mixer, a detent operating lever operatively connected to the said timing mechanism, a locking pawl releasably connecting the detent operating lever and the detent, means for automatically releasing the pawl and returning the detent to its original position after the detent has been actuated, and means for resetting the starting lever.

33. In combination, a mixer, discharge means for the mixer, a constantly driven gear, a second gear operatively connected to the discharge means and adapted to be intermittently driven by the constantly driven gear, a starting lever for moving one of the gears into initial mesh with the other gear to produce an actuation of the discharge means, a detent normally holding the starting lever in inoperative position, timing mechanism for the mixer, a detent operating lever operatively connected to the said timing mechanism, a locking pawl operatively connecting the detent operating lever to the detent, cam means for automatically releasing the pawl after the detent has been actu-

ated, and means actuated by the gears for resetting the starting lever.

34. In combination, a mixer, discharge means for the mixer, a constantly driven gear, a second gear operatively connected to the discharge means and adapted to be actuated intermittently by the constantly driven gear to produce an actuation of the discharge means, a starting lever for moving one of the gears into initial mesh with the other gear, a detent for holding the starting lever in inoperative position, timing mechanism for the mixer, a detent operating lever operatively connected to the timing mechanism, a locking pawl connecting the detent operating lever and the detent, said locking pawl having a cam portion which engages a part of one of the gear members for automatically releasing the pawl after the detent has been actuated, and means for resetting the starting lever.

35. In combination, a mixer, discharge means for the mixer, a constantly driven gear, a second gear operatively connected to the discharge means and adapted to be intermittently actuated by the constantly driven gear to produce the desired actuations of the discharge means, a starting lever adapted to move one of the gears into initial engagement with the other gears, a detent normally holding the starting lever in inoperative position, a manually operated means connected to the detent, timing mechanism for the mixer, an operative connection between the timing mechanism and the detent, and means for preventing actuation of the detent by the manual means until after the completion of the operation of the timing mechanism.

36. In combination, a mixer, discharge means for the mixer, power mechanism for operating the discharge means, and an automatically releasable mechanism between the power mechanism and discharge means.

37. In combination, a mixer, discharge means for the mixer, power mechanism for operating the discharge means, and a connection including a safety clutch interposed between the power mechanism and discharge means and permitting the power mechanism to work without operating the discharge means.

38. In combination, a mixer, discharge means for the mixer, power mechanism for operating the discharge means, and a connection between the power mechanism and discharge means including a clutch comprising spring pressed members having corresponding cam portions which normally interlock but will ride over each other and automatically release the connection if abnormal resistance is encountered in the operation of the discharge means.

39. In combination, a mixer, discharge means for the mixer, a discharge operating

shaft, an arm loose on the shaft, power means operatively connected to the arm, and a clutch connection between the arm and the shaft which will be automatically released if abnormal resistance is encountered in operating the discharge means.

40. In combination, a mixer, discharge means for the mixer, a discharge operating shaft, an arm loose on the shaft and formed with a clutch face, power means operatively connected to the arm, a clutch member keyed upon the shaft and formed with a clutch face adapted to cooperate with the clutch face on the arm to provide a releasable connection between the arm and shaft, and yielding means acting on the clutch member to hold the two clutch faces normally in engagement with each other.

41. In combination, a mixer, discharge means for the mixer, a discharge operating shaft, an arm loose on the shaft and formed with a clutch face, power means connected to the arm, a hollow clutch member keyed on the shaft and having a clutch face adapted to engage the clutch face of the arm to produce a releasable connection between the arm and the shaft, and a spring housed within the hollow clutch member and normally acting upon the same to hold the two clutch faces in operative engagement with each other.

42. In combination, a mixer, discharge means for the mixer, a constantly driven power member, a second power member driven intermittently thereby and operatively connected to the discharge means, timing mechanism for the mixer, means controlled by the said timing mechanism for causing the intermittently driven power member to be actuated by the constantly driven power member, and means for preventing the second power member from being prematurely brought into cooperative relation with the constantly driven power member.

43. In combination, a mixer, discharge means for the mixer, a constantly driven gear, a gear adapted to be driven intermittently by the constantly driven gear and operatively connected to the discharge means, starting means for initially bringing the two gears into mesh to actuate the discharge means, and means controlled by the starting means for preventing the gears from being brought into mesh independently of the starting means.

44. In combination, a mixer, discharge means for the mixer, a constantly driven gear, a gear adapted to be driven intermittently by the constantly driven gear and operatively connected to the discharge means, pins projecting from the intermittently driven gear, a starting lever having a portion which projects into the path of one

of the pins for cooperation therewith to prevent the gears from being brought prematurely into mesh and having a head which is adapted to engage another pin to initially rotate the gear to bring the gears into mesh, the first mentioned portion being swung into inoperative position when the head is brought into operative engagement with one of the pins, and means for actuating the starting lever and detent controlling the starting lever.

45. In combination, a concrete mixer, discharge means therefor, power mechanism for operating the discharge means and a yieldable connection between the power mechanism and the discharge means permitting the discharge means to remain stationary upon meeting an obstruction, whilst the discharge means continues to operate.

46. In combination, a concrete mixer, discharge means therefor, comprising a chute, power mechanism for operating the chute and a safety coupling between the power mechanism and the chute establishing a connection enabling the power mechanism to operate while the chute is stopped in its movement against operation thereby through meeting an obstruction or the like.

47. In combination, a concrete mixer, means for charging aggregates therewith, a discharge for the mixer, power means for operating the discharge, a batchmeter arranged to intermittently connect the power means with the discharge and control means intermediate the batch-meter and said power means.

48. In combination, a concrete mixer, a discharge means therefor, power means including constantly driven gear, a second gear, a batchmeter, and means operable from the batchmeter for causing engagement of the second gear with the said constantly driven gear, together with an operating connection between the second gear and the discharge means.

49. In combination, a concrete mixer, a discharge means therefor, power means including constantly driven gear, a second gear, a batchmeter, and means operable from the batchmeter for causing engagement of the second gear with the said constantly driven gear, together with an operating connection between the second gear and the discharge means, said gears having inter-meshing teeth, and the second gear having interrupted tooth portions such that after it has been engaged with the constantly driven gear it may at a predetermined time become disengaged to discontinue the operation of the discharge means.

In testimony whereof I affix my signature.

GEORGE E. WEBB.
